NO. 11,663

MARCH 2, 1880

UNITED STATES PATENT OFFICE.

WALTER J. GADSBY, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,663, dated March 2, 1880.

Application filed January 30, 1880. Term of patent 3½ years.

To all whom it may concern:

Be it known that I, WALTER J. GADSBY, of Boston, in the county of Suffolk and State of Massachusetts, have invented and produced a new and original Design for Carpets, of which the following is a specification.

My design consists of a combination of floral designs, foliage or leaf-work, and acorns thickly arranged, as shown in the accompanying photograph, forming a part of this specification.

The principal features of the design are the acorns a, oak-leaves b, pendent flowers c, elongated leaves d, and the foliage designs f g, and flowers h i.

I claim—

The design for a carpet, substantially as shown and described.

In testimony whereof I have signed my name to this specification, in the presence of two subscribing witnesses, this 27th day of January, 1880.

Witnesses: WALTER J. GADSBY,
THOMAS J. STEARNS,
C. F. BROWN.
